UNITED STATES PATENT OFFICE

NAPOLEON B. DOUGLASS, OF BERKELEY, CALIFORNIA, ASSIGNOR TO THE ROME COMPANY, INC., OF ROME, NEW YORK, A CORPORATION OF NEW YORK

WALL BED

Application filed March 30, 1929. Serial No. 351,176.

This invention relates to wall beds and pertains especially to a reversible wall bed mounted on a panel in an opening in the wall and adapted to be turned through an arc of 180°, so that the bed may be exposed into the room, and ready for use, or turned into the closet and concealed when not in use.

A particular object of the present invention is to provide a practical wall bed of this character which is a simple and economical structure, and so constructed and arranged that a full-sized, double bed may be made to turn in and out of a closet, having an opening of less width than the bed; the closet having an ordinary door of the usual dimensions, for closing it when not in use; the bed being mounted entirely independent of the door and in no wise having its movements affected or controlled by the door itself.

The invention possesses other advantageous features, which, with the foregoing will be set forth in the following description where I shall outline in full that form or embodiment of the invention which I have selected for illustration in the drawings accompanying and forming part of the present specification. The novelty of the invention will be included in the claims succeeding said description. From this it will be apparent that I do not restrict myself to the showing made by said drawings and description as I may adopt many variations within the scope of my invention as expressed in said claims.

In the drawings—

Fig. 1 is a perspective view showing my improved support affixed to one side of a door opening, and

Figs. 2, 3, 4, and 5 are plan views, partially in section, showing my improved support in the various positions which it assumes in moving the bed from its exposed to its concealed position.

Referring now to Fig. 1, 10 designates the jamb of a suitable door opening such as is provided in connection with concealed wall beds. Attached to the jamb 10, I show bearing supports 11 and 12 arranged in vertical alignment, one above the other. Interposed between the supports 11 and 12, I provide a pivoted standard 13 which carries arms 14

and 15 at the top and bottom thereof. These arms 14 and 15 are adapted to move with the standard 13, and are adapted at their outer ends to engage inwardly projecting arms 16 and 17 carried by a member 18. The member 18 is adapted to pivotally engage the head frame 19 of a bed 20, this pivotal engagement being provided by means of suitable bearing members 21 and 22 which engage respectively the top and bottom projecting ends of the member 18.

With the structure above described, it will be apparent that, with a bed mounted in this manner with so many possible pivotal points, the bed in being moved might travel through an infinite number of different paths and, for this reason, I have provided means which will restrict the movement of the bed about its pivotal points in such a manner that it will at all times move in a path closely adjacent the jamb of the door opening to which it is supported, so that the bed will pass through a door opening of minimum size.

On this point, it should be stated that at the present time the doors provided for openings of the character contemplated are usually made somewhat larger than an ordinary door, the door being in most instances approximately 3 feet across. This, of course, as will be readily appreciated, tends to defeat the very object to be sought, that is, of concealing the bed since such a large door in a wall immediately suggests something unusual. In order to accomplish this latter and preferred result, I provide suitable links 23 and 24 which operate in conjunction with the articulated support so as to limit the movement with respect to each other of the various members at their pivotal points. The link 23, as shown in Fig. 1 of the drawings, is connected at one end to a point intermediate the ends of the arm 16, and at its other end it is connected to a point 25 which is located off-center with respect to the center of the support 11. This link 23, as will be readily seen, serves to limit the pivotal movement between the projecting arms 14 and 16 and serves to cause the member 18 to travel closely adjacent the door

jamb 10. The link 24, as shown in this figure of the drawings, is connected to the bed frame 19 at one end and at its other end to a projection 26 formed upon the arm 15. 5 This link 24, as will be readily understood, serves to limit the freedom of movement of the bed frame 19 with respect to the member 18 and at the same time it also serves to pivot the bed upon the member 18 in such a 10 manner that its extreme edges will travel in a direction so as to include only a minimum area of floor space.

With a mounting of the above described character, I have found that it is possible to 15 support a full-sized bed so that it can be moved in and out through a door opening having dimensions as small as 2 feet 4 inches and, in fact, with a door of this dimension it is also possible for the operator to pass in 20 and out of the closet when the bed is in either of its positions.

Having thus described my invention, what I claim and desire to secure by Letters Patent is—

25 1. In combination with a bed frame, movable into and out of a receptacle through a door in the receptacle, a supporting link pivoted at a point within the receptacle and behind the door jamb, a pair of parallel 30 links pivoted at one end to said supporting link and at their other ends to said bed frame, and a guide link pivotally supported at one end within the receptacle and behind the jamb and pivoted at its other end to a 35 point that is fixed with relation to one of said parallel links.

2. In combination with a bed frame, movable into and out of a receptacle through a 40 door in the receptacle, a supporting link pivoted at a point within the receptacle and behind the door jamb, a pair of parallel links pivoted at one end to said supporting link and at their other ends to said bed frame, and a guide link pivotally supported 45 at one end within the receptacle and behind the jamb and pivoted at its other end to a point that is fixed with relation to one of said parallel links, said guide link being curved to extend around one edge of the 50 door jamb when the bed frame is disposed outside of the receptacle and being entirely disposed behind the door jamb when the bed is within the receptacle.

NAPOLEON B. DOUGLASS.
